DESIGN FOR A FRAME FOR A HAND MIRROR OR MAGNIFYING GLASS

Theodore Friedman, New York, N. Y.

Application April 20, 1945, Serial No. 119,112

Term of patent 7 years

(Cl. D86—10)

To all whom it may concern:

Be it known that I, Theodore Friedman, a citizen of the United States of America, residing at New York, in the county and State of New York, have invented a new, original, and ornamental Design for a Frame for a Hand Mirror or Magnifying Glass, of which the following is a specification, reference being made to the accompanying drawing, forming a part thereof.

Fig. 1 is a front view of a frame for a hand mirror or magnifying glass embodying my new design; and

Fig. 2 is a side view thereof.

Fig. 3 is a sectional view taken on line 3—3 of Fig. 1.

The back of the frame, not shown, is substantially plain.

I claim:

The ornamental design for a frame for a hand mirror or magnifying glass, substantially as shown and described.

THEODORE FRIEDMAN.
